UNITED STATES PATENT OFFICE.

HERVEY J. WHEELER, OF BROOKLYN, NEW YORK, ASSIGNOR TO H. J. WHEELER SALVAGE CO., INC., OF BROOKLYN, NEW YORK, A CORPORATION OF NEW YORK.

PUMPING APPARATUS.

1,405,173.

Specification of Letters Patent. Patented Jan. 31, 1922.

Application filed June 16, 1920. Serial No. 389,283.

To all whom it may concern:

Be it known that I, HERVEY J. WHEELER, a citizen of the United States, residing in the city of New York, borough of Brooklyn, in 5 the county of Kings and State of New York, have invented a certain new and useful Improvement in Pumping Apparatus, of which the following is a specification.

The invention relates to means for lifting 10 and transferring material from a lower to a higher level, and as it has been carried out in practice is designed more particularly for pumping the residue from the oil tanks of oil-burning vessels.

15 This waste material is generally a thick greasy mass, almost jelly-like in consistency, very unpleasant and difficult to handle. Its removal by ordinary methods is a slow and exceedingly dirty operation; usually the material is dipped from the tanks in buckets 20 which are passed by hand to the main deck of the ship, emptied into barrels and passed back empty for refilling at the oil-tanks. The barrels as filled are lowered over the side to 25 a barge or lighter to be carried away. The material is of such nature as to preclude its handling by a force-pump, and as the lift from the tank-covers to the ship's rail is generally from thirty to fifty feet, it is im- 30 practicable to remove it by ordinary suction pumping operations.

The object of the invention is to provide means for transferring the material directly from the oil-tanks to overside receptacles. 35 I have discovered that with a combined vacuum-suction and siphon action, this and other materials may be raised and delivered overside through a hose, thus permitting the operation of cleaning the oil-tanks to be 40 quickly and economically performed while avoiding the discomfort and dirt attending the usual operation.

The invention consists in certain novel features and arrangements of parts by which 45 the above objects are attained, to be herein-after described and claimed.

The accompanying drawings form a part of this specification and show the apparatus in the form now being successfully operated.

50 Figure 1 is an incomplete transverse section of a vessel, and end elevation of a barge

alongside, showing a portion of the apparatus carried thereon.

Figure 2 is a plan view on a larger scale, 55 of the barge and its pumping equipment.

Figure 3 is an elevation of the suction nozzle on a still larger scale.

Figure 4 is a corresponding vertical section, taken on the line 4-4 in Figure 3.

Figure 5 is a plan view of the under face 60 of the nozzle.

Similar letters of reference indicate the same parts in all the figures.

A is a ship having tanks A¹ as usual in which oil for the furnaces is carried below 65 the hold, and containing the waste oil residue to be removed.

B is a barge or like vessel ranged alongside the ship and carrying the pumping equipment. C indicates the location of an 70 engine or motor, not shown, having a shaft C¹ and pulley C², and D is an air pump having a shaft D¹ and pulley D² driven by a belt C³ from the engine.

F F are cylindrical exhaust tanks of large 75 capacity carried horizontally on the barge and arranged in tandem pairs on each side thereof. The tanks of each pair are connected at their adjacent ends on the upper face by pipes F¹ F¹ with a controlling valve F² for each tank, and the pipes F¹ are connected by a transverse pipe F³ from which extends a pipe F⁴ to the suction side of the air-pump D. This exhaust system is made up in the present apparatus of 2½ inch pipe 80 through which a high vacuum is maintained in the tanks by the action of the air-pump.

The opposite ends of the tanks are connected by transverse pipes G¹ G¹ with a valve G² for each tank, and from each of the pipes 90 G¹ extends a branch pipe G³ controlled by a valve G⁴ which join together at a hose connection G. This suction line is of 2 inch pipe and the hose connection G receives a 2 inch hose H which extends upwardly from 95 the barge, over the rail of the ship A, and thence downwardly through any available passage-ways to the oil tanks A¹.

On the free end of the hose is a suction nozzle H¹, see Figures 3, 4 and 5, reduced 100 from 2 inches to 1½ inches and flattened at the end, as shown in Figure 5, to form a

suction orifice h $\frac{1}{2}$ of an inch wide by 2 inches long. Above the suction orifice and shown as in the larger portion of the nozzle, is a small air inlet aperture h^1 controlled by 5 an air-cock H^2 .

The capacity of the air-pump is sufficient to maintain a high vacuum in the exhaust tanks F, 25 inches of mercury or higher, when the suction orifice h is not submerged 10 and the air-cock H^2 open.

In operating, the nozzle is thrust into the material which is drawn up through the in-board leg of the hose and down through the outboard leg, and through the suction line

15 G¹ G³ to the exhaust tanks. When the latter are filled or partly filled the operation is discontinued and the material drawn off from the tanks F by any suitable delivery means, shown as the discharge pipes J con-

20 nected to the lower faces of the exhaust tanks and each controlled by a valve J¹.

The nozzle is lowered to follow the level of the material as the latter falls, and is transferred from one to another as the oil tanks

25 are successively emptied.

The function of the air-inlet aperture h^1 is to supply a quantity of air to the mass of thick jelly-like material entering the nozzle H^1 and agitate or crack such material me- 30 chanically by mixing air therewith and thus effecting an emulsion or mechanical dilution essential to the transfer. In submerging the suction orifice h of the nozzle care must be taken not to submerge the air-inlet 35 aperture h^1 controlled by the air-cock H^2 . By adjusting the latter the proportion of air may be varied as required by the character of the material to be transferred.

It will be noted the material does not 40 enter the pump, the function of which is simply to maintain the high vacuum in the exhaust tanks F F.

By the use of this apparatus the operation of emptying and cleaning the oil-tanks is 45 performed expeditiously and without the annoyance and the fouling of the ship due to ordinary methods, thus effecting a great saving in both time and expense.

With the apparatus as shown and de- 50 scribed the dense residue in the oil-tanks has been raised and delivered through an inboard leg of hose having a vertical height from twentyfive to fortysix feet in various situations with a vacuum indicated by 55 twentyeight inches of mercury.

It is believed that by continued practical

employment of the apparatus other forms and proportions may be developed by which the efficiency or capacity may be further increased, but the sizes and proportions herein given are known to attain the results stated. 60

Although the invention is shown and described as designed to pump the residue from the oil-tanks of oil-burning ships, it will be understood that it will serve successfully in 65 transferring liquids, semi-liquids, or other materials in any situations in which a lift is required above that attainable by the direct action of a suction pump.

I claim:—

70 1. The herein described method of transferring viscous material directly from the interior of a maritime vessel to an overside receptacle, which consists in creating a high vacuum in said receptacle to thereby suck such material to an elevation and deliver it directly into said receptacle, and admitting air in small quantities into the suction end of the conveying pipe to emulsify said material.

75 2. The apparatus described, comprising a series of exhaust tanks, an air-pump, a system of unrestricted exhaust pipes connecting said tanks to said pump, means for driving said pump to maintain a high 80 vacuum in said tanks, a system of suction pipes of less diameter than said exhaust pipes, connecting said tanks, a hose connected to said suction system and of the same diameter as said suction pipes, and a 85 suction nozzle having a body of less diameter than said hose and a suction orifice of less area than such body.

90 3. The apparatus described, comprising a series of exhaust tanks, an air-pump, a sys- 95 tem of unrestricted exhaust pipes connecting said tanks to said pump, means for driving said pump to maintain a high 100 vacuum in said tanks, a system of suction pipes of less diameter than said exhaust 105 pipes, connecting said tanks, a hose connected to said suction system and of the same diameter as said suction pipes, a suction nozzle having a body of less diameter than said hose and a suction orifice of less area than such body, and an air-inlet aperture in such body above such orifice, and an air-cock controlling such aperture.

105 In testimony that I claim the invention above set forth I affix my signature.

HERVEY J. WHEELER.
